UMBRELLA HANDLE

Heinz Weber, Hilden, Germany, assignor to Telesco
Brophy Limited, Montreal, Quebec, Canada

Filed Oct. 20, 1969, Ser. No. 19,641

Term of patent 14 years

Int. Cl. D3—03

U.S. Cl. D88—3

FIG. 3

FIG. 1

FIG. 1 is a plan view of an umbrella handle;
FIG. 2 is an end view of an umbrella handle;
FIG. 3 is an end view taken from the stick end of the umbrella handle; and

FIG. 4 is a vertical cross section taken along the line
4—4 in FIG. 1.

The essential feature of my design resides in the handle portion.

I claim:

The ornamental design for an umbrella handle, as shown and described.
